UNITED STATES PATENT OFFICE

2,425,339

STOKER APPARATUS

Leonard C. Neufeld, Des Moines, Iowa

Application January 22, 1945, Serial No. 573,936

4 Claims. (Cl. 302—17)

1

This invention relates generally to coal stokers of residential type having a hand-fed fuel hopper, and in particular to an attachment for such stokers adapted to feed fuel to the hopper by a suction action.

The convenience of stoker heated homes is offset in many installations by the requirement of hand feeding the stoker hopper. Even though such feeding is required at infrequent intervals, it involves a rather close locating of the fuel within the hopper opening to prevent the spilling of fuel about the floor. Further fuel to be burned in the stoker is generally carried in a bin adjacent to or removed from the stoker hopper. Thus when the fuel bin is partially emptied the stoker operator must walk back and forth across coal dust on the floor within the bin so that not only is the floor about the stoker continuously tracked and dirtied, but oftentimes the coal dust is tracked into the living quarters of the home. As a result, unless the floor about the stoker is frequently swept, dust, dirt and loose fuel quickly accumulate and are soon carried throughout the room in which the stoker is located so as to give an over-all unclean appearance.

A further objection to the usual hand-fed residential stoker is the fact that appreciable shovelling of coal, as well as transport of the coal from a bin into the stoker hopper, is required for each filling of the hopper. Appreciable manual effort is thus exerted so that filling of the hopper is generally a chore for the men of a household. On their absence from the home this chore is oftentimes a hardship to remaining members of the household.

It is an object of this invention, therefore, to provide an improved means for feeding fuel to hand-fed stokers.

Another object of this invention is to provide an attachable mechanical means for feeding a stoker hopper which is adapted to be operated by the usual stoker motor regardless of the operation of the motor as required by any heat demand on the stoker.

A further object of this invention is to provide a mechanical means for feeding fuel into a stoker hopper which is capable of picking up all loose coal, coal dust and ash particles from about a stoker and within a coal bin so as to maintain the floor space about the stoker in a clean condition.

A still further object of this invention is to provide a mechanical means for feeding a usual hand-fed fuel hopper in a residential stoker.

2

which requires a minimum of manual effort in its operation so that fuel can be supplied to the hopper by any member of the household.

A feature of this invention is found in the provision of a suction-creating unit which is attachable to a usual stoker hopper for operation from the stoker motor. The outlet of the suction unit is open to the top portion of the hopper for discharging fuel into the hopper, while the inlet of the suction unit is provided with a flexible conduit having its free end movable to a fuel storage bin or the like to pick up fuel for feeding to the hopper.

Yet another feature of this invention is found in the provision of a suction-producing unit for feeding fuel into a stoker hopper which is operated from the stoker motor through a clutch device. A control switch for the motor circuit is closed on manual operation of the clutch to a "throw in" or connecting position, with the clutch being moved to a disconnecting or "throw out" position and the control switch to an open position in response to the rise of the fuel in the hopper to a predetermined level.

Further objects, features and advantages of this invention will become apparent from the following description when taken in connection with the accompanying drawings in which:

Fig. 1 is a longitudinal sectional view through a stoker hopper showing the attachment of this invention in assembly relation therewith;

Fig. 2 is a detail sectional view on the line 2—2 in Fig. 1;

Fig. 3 is a plan view of a stoker hopper with parts broken away to more clearly show the assembly of the attachment of this invention therein;

Fig. 4 is a sectional view taken on the line 4—4 in Fig. 3;

Fig. 5 is an enlarged plan view showing the suction-producing unit of the hopper feeding means of this invention and its assembly in a driven relation with the operating motor of a stoker;

Fig. 6 is a sectional view taken on the line 6—6 in Fig. 5;

Fig. 7 is an exploded view in side elevation of a separable pulley forming a part of the attachment of this invention;

Fig. 8 is a sectional view taken on the line 8—8 in Fig. 7; and

Fig. 9 is a diagrammatic showing of the circuit for the stoker motor.

Referring to the drawings there is illustrated in Figs. 1 and 2 a housing 10 for a stoker ap-

paratus including a fuel hopper or compartment 11, and a motor compartment 12. The top of the fuel hopper 11 is provided with a cover 26 for an opening 27 through which fuel is usually fed by hand into the hopper. A screw conveyor 13 for carrying fuel from the hopper 11 to the stoker retort (not shown) is extended across the bottom portion of the hopper and within the motor compartment 12 for connection with a combination speed reduction and transmission unit 14 having a driven shaft 16.

Mounted upon the shaft 16 is a multiple sheave or pulley unit 17 which is connected through a belt 18 with a multiple sheave unit 19 carried on the projected end 21 of a shaft 22 of an electrical motor 23. The motor 23 is located within the compartment 12 and is supported on a casing 24 of the fuel conveyor 13.

Also mounted on the shaft end 21, and to the outside of the sheave unit 19, is a blower or fan 26 having an air outlet 27 connected through an air conduit 28 with the stoker retort to supply combustion air thereto.

It is seen, therefore, that on operation of the motor 23 the blower 26 is operated at the speed of the motor 23, while the fuel conveyor 13 may be operated at varying speeds depending upon the relative position of the belt 18 on the multiple sheave units 17 and 19. The above described stoker construction and operation is common in available commercial stokers.

The attachment of this invention providing for a mechanical feeding of fuel into the hopper 11 from a storage or coal bin comprises a suction-producing unit or blower 31 located within the compartment 12 above the combination unit 14. The suction unit housing 32 (Fig. 5) is secured to a side wall 33 of the compartment 12 by screws 34 or like suitable means. A shaft 36 for the suction unit 31 is rotatably supported in the housing 32 and is arranged above and in a parallel relation with the shaft 16 of the combination unit 14. The shaft 36 has a pulley 37 mounted at its inner end and connected through a belt 38 with a pulley 39 rotatably mounted on the motor shaft 22 between the multiple sheave unit 19 and the motor hub 40.

As shown in Figs. 7 and 8 the pulley 39 is of a split type comprised of separable mating half members 42 so that the pulley may be positioned on the shaft 22 without the removal from the shaft of the sheave unit 19 or the blower 26. It is contemplated that screws 41 for securing the mating half members 42 together be inclined inwardly of the pulley hub 43 to facilitate access to the screws 41 by a screw driver or the like for tightening purposes.

The side face of the pulley 39 adjacent to the sheave unit 19 is provided with a clutch or friction ring 44 (Figs. 6 and 8) which is frictionally engageable with the side face 46 of the sheave unit 19, on axial movement of the pulley 39 toward the sheave unit 19, so as to constitute a friction clutch device for connecting and disconnecting the pulley 39 in a driven relation with the motor shaft 22. An axial movement of the pulley 39 against the sheave unit 19 is accomplished by means including a clutch lever 47 (Figs. 4 and 5) having one end 48 slidably extended through an opening 49 in a inclined top wall 51 of the housing 10, while its opposite end 52 is of a bifurcated or U-shape construction slidably supported in a straddling relation with the motor shaft 22 between the pulley 39 and the motor hub 40.

A flat spring 53 is secured to one side of the clutch lever 47 so as to be movable against the motor hub 40 on actuation of the clutch lever 47 to a "throw in" position inwardly of the compartment 12, or to the right as viewed in Figs. 4 and 5. As clearly appears in Fig. 4, the free end of the spring 53 is of a U-shape construction, corresponding to the shape of the lever end 52, and is bowed outwardly from the lever 47 so that on inward actuation of the lever the spring 53 is pressed between the lever end 52 and the motor hub 40 to in turn yieldably urge the pulley 39 into frictional engagement with the sheave unit 19 for rotation therewith.

The clutch lever 47 adjacent its end 48, and within the compartment 12, is provided on its top side, as viewed in Fig. 4, with a laterally extended projection 55 of a tooth shape having an inclined cam surface 57 and a stop portion 58. On the lower side of the lever 47 and arranged oppositely from the projection 55 is a lateral projection 59 having a cam portion with inclined sides 61 and 62 and an intermediate high side or spot 63.

The lever projection 55 is operatively associated with a control rod or shaft 64 having a straight portion 65 extended adjacent to and below the top wall 51 of the housing 10 and pivotally or rockably supported in bearings 66 secured to the under side of the wall 51. The straight portion 65 of the control rod 64 has a crank arm 67 at its lower end, as viewed in Figs. 1 and 4, which extends downwardly from the top wall 51 so that its free end rides in a following relation on the cam surface 57 of the lever projection 55. The opposite or upper end of the control rod 64 is formed with a somewhat similar crank arm 69 engageable with a radial extension 75 on the top of a vertically movable sleeve 72 located in the fuel hopper 11 (Figs. 1 and 2).

The sleeve 72 is guidably supported for vertical movement on an upright portion 73 of a fuel-carrying conduit or pipe 74 connected with the outlet 80 of the suction-producing unit 31. The conduit 74 from the suction unit 31 is extended along the under side of the housing top wall 51 adjacent to the straight portion 65 of the control rod 64 and terminates in the downwardly bent upright portion 73 at a position near the top of the fuel hopper 11. The lower end of the sleeve 72 carries a relatively wide annular flange 76 the periphery 77 of which is engageable with the top surface 78 of the fuel fed into the hopper 11 for a purpose which will later be fully explained. A stop ring 101 at the lower end of the upright pipe portion 73 prevents the sleeve 72 from falling into the hopper when the fuel in the hopper drops to a low level.

The projection 59 on the lever 47 (Fig. 4) is operatively associated with a control switch 79 connected in the circuit for the motor 23 and supported within the motor compartment 12 on a bracket 81 mounted on the housing wall 51 by screws or the like 82. The switch 79 is of a usual construction and includes a pair of actuating members 83 and 84 which are mutually responsive in operation to open and close the circuit for the motor 23. In other words on depressing the actuating member 84 the actuating member 83 is concurrently raised from a depressed position to provide a circuit closing position for the switch. Conversely on depression of the actuating member 83 the member 84 is raised from a depressed position to provide a circuit opening position of the switch. This action is clearly apparent from

a consideration of the circuit diagram in Fig. 9 in which the actuating members 83 and 84 are diagrammatically illustrated as pivoted at opposite ends of a lever 87, which in turn is pivoted intermediate its ends at 88. The actuating member 83 is concurrently movable with a contact conductor 89 for connecting and disconnecting the switch terminals 91 as will be later explained.

A tension spring 92 is connected at one end to a projection 93 on the lever 47 and at its opposite end to an extension 94 on the switch supporting bracket 81 and acts to continuously urge or bias the lever 47 to a clutch opening or throw-out position.

The control circuit for the motor 23 (Fig. 9) is connected with supply lines 103 and 104 with a suitable source of electrical power. The control switch 79 is illustrated as being connected in series with the supply line 104, with depression of the actuating member 84 closing the line 104 by the contact engagement of the conductor 89 across the switch terminals 91 in the line 104, and with the depression of the actuating member 83 moving the conductor 89 away from a terminal connecting position. An automatic switch device, designated generally as 106, is connected with the supply line 104 in parallel with the control switch 79 so as to be operable independently of the switch 79 for opening and closing the motor circuit in response to any heat demand upon the stoker.

In the operation of the invention assume the fuel hopper 11 to be partially empty and the stoker motor 23 at a standstill, in other words in a condition where there is no heat demand upon the stoker so as to require an operation of the motor 23. Assume also that the lever 47 is in its normal throw-out position, maintained by the tension spring 92, and shown in full lines in Fig. 4. This throw-out position of the lever 47 corresponds to the open position of the switch 79 shown in Fig. 9.

To fill the hopper 11 a manual grip 95 on the projected end 48 of the lever 47 is manually pushed inwardly, or toward the right as viewed in Fig. 4, against the pressure of the spring 92 to move the lever 47 to its dotted line position also shown in Fig. 4. During this movement of the clutch lever 47 to a clutch throw-in position the spring 53 is pressed between the lever 47 and the motor hub 40 to move the pulley 39 into frictional engagement with the multiple sheave unit 19. Concurrently with this frictional engagement of the pulley 39 for rotation with the sheave unit 19 the high spot 63 on the lever projection 59 moves out of engagement with the switch actuating member 83 and into engagement with the switch actuating member 84, by the action of the cam side 61, to depress the member 84 to a position for closing the motor circuit. It is thus seen that the motor 23 is set into operation concurrently with the frictional engagement of the pulley 39 with the sheave unit 19, to provide for the operation of the suction unit 31 through its belt connection 38 with the pulley 39.

The lever 47 is maintained in its dotted line position, shown in Fig. 4, by the engagement of the crank arm 67 with the stop portion 58 on the lever projection 55. This stop engagement is accomplished by the pivotal movement of the control rod 64 in response to the travel of the crank arm 67 upwardly on the cam portion 57 of the projection 55, with the arm 67 on reaching the top end of the cam portion 57 dropping into engagement with the stop portion 58 by the action of gravity.

The inlet 94 of the suction unit 31 is connected with a flexible hose or conduit 96 extended outwardly from the housing 10 and provided at its free end with a suction or pick-up nozzle 97.

5 The hose 96 may be of any suitable length to reach the fuel stored in a bin or the like for burning in the stoker. With the suction unit 31 in operation the stoker operator merely moves the pick-up device 97 over the fuel which is to be supplied to the hopper. This fuel is picked up by the suction action of the unit 31, carried through the hose 96 into the suction unit 31, and then through the fuel passage or pipe 74 for discharge therefrom into the fuel hopper 11 through the upright pipe portion 73.

10 With the filling of the hopper the fuel level approaches the lower end of the pipe portion 73, as viewed in Fig. 1. As the fuel level continues to rise it will be blown out from below the upright pipe portion 73 so as to form a substantially circular hole 98, the periphery 99 of which substantially defines the topmost level 78 of the fuel in the hopper. With the continued supply of fuel into the hopper the fuel at the periphery 99 enga-

20 ges the periphery 77 of the flange 76 whereby the flange 76 and in turn the sleeve 72 are pushed upwardly in response to the rise in the level of the fuel. During this upward movement of the sleeve 72 the crank arm 69 on the control rod 64

25 is engaged by the radial sleeve projection 75 whereby the rod 64 is pivotally moved to disengage the crank arm 67 from its engaged position with the stop portion 58 on the projection 55 of the lever 47.

30 On movement of the crank arm 67 out of engagement with the stop 58 the lever 47 is moved outwardly or to the left, as viewed in Figs. 1 and 4, to its throw-out position shown in full lines in Fig. 4. This movement of the clutch lever 47

35 permits the pulley 39 to move out of frictional engagement with the multiple unit 19 concurrently with the release of the switch-actuating member 84 from its depressed position closing the motor circuit, and the depression of the actuating member 83 to a circuit opening position. Thus the frictional disengagement of the pulley 39 with the sheave unit 19, and in turn the stopping of the suction unit 31, takes place concurrently with the stopping of the motor 23 in response to the rise of fuel in the hopper 11 to a predetermined level and independently of any attention by the stoker operator. In other words even though the fuel storage bin is located in a position at which the hopper is out of the vision of the operator, the suction unit 31 will be automatically stopped on filling of the hopper so as to preclude any constant attention by the operator as to the filled condition of the hopper.

40 Assuming the motor 23 to be in operation by the action of the automatic switch 106 in response to a stoker heat control unit, such as a room thermostat or the like (not shown), the actuating lever 47 is manually moved to its dotted line position shown in Fig. 4 in the manner described above. Since the motor 23 is already in operation the closing of the motor circuit by the switch 79 in no way affects such operation by virtue of the connection of the switch 79 in parallel with the automatic switch 106. The pulley 39, however, is moved into frictional engagement with the multiple unit 19 to provide for the operation of the suction unit 31. In the event the automatic switch 106 is actuated to its open position during the time the hopper 11 is being filled, the motor 23 will continue in operation to drive

45

50

55

60

65

70

75

the suction unit 31 by virtue of the motor circuit, being closed by the switch 79. The hopper filling operation will thus proceed uninterrupted.

When the hopper is filled to a predetermined level, as above explained, the sleeve 72 is moved upwardly to rock the rod 64 and provide for the release of the crank arm 67 with the stop portion 58 to disengage the pulley 39 from the multiple sheave unit 19, and to actuate the switch 79 to its open position to stop the operation of the motor 23. Should the motor be maintained in operation by the automatic switch 106 for the full time required for filling the hopper 11, the pivotal movement of the crank arm 67 away from the stop 58 will merely actuate the switch 79 to its open position, so that the motor 23 will stop on the later opening of the automatic switch 106.

It is apparent that in the operation of the suction unit 31 air will be discharged into the fuel hopper 11 along with fuel so as to create an air pressure within the hopper 11. This pressure is released through an air outlet 110, in the housing top wall portion 111, which is provided with a filter 112 to prevent the escape of coal dust into the stoker room. Also as clearly appears from a consideration of Fig. 1 the air pressure pocketed within the blow hole 98 may act alone or in conjunction with the rise of the fuel level in the hopper 11 to move the flange 76 and in turn the sleeve 72 upwardly to rock the control rod 64.

It is thus seen that the invention provides a mechanical means for feeding a usual hand-fed stoker hopper such that a minimum of effort and attention is required by the stoker operator to fill the hopper. The operator need only operate the clutch member 47 to its throw-in position for frictionally engaging the pulley 39 with the multiple sheave unit 19 and then manipulate the suction nozzle 97 over the fuel to be supplied to the hopper. When the hopper is filled the suction unit 31 is automatically stopped and the stoker conditioned for normal operation without any attention by the operator. It is obvious, of course, that the nozzle 97 is movable about the housing 10, as well as to fuel stored remotely from the stoker, so that at the beginning of a hopper filling operation the nozzle 97 may be utilized to pick up dirt, coal dust and any ash particles which might be lying on the floor around the stoker. As the coal bin becomes emptied all coal dust on the open floor space within the coal bin may be continuously picked up so as to eliminate any need of the operator tracking back and forth across a coal dust covered floor.

It is to be understood that this invention is not limited to any particular type of stoker apparatus, and may be applied to many type stokers now in commercial use. It is to be understood also that although the invention has been described with respect to a single embodiment thereof that it is not to be so limited since changes and modifications can be made therein which are within the full intended scope of this invention as defined by the appended claims.

I claim:

1. In stoker apparatus, the combination with a housing having a fuel hopper, of means for feeding fuel by suction into said hopper including a suction-producing means supported on said housing, a motor, means for operating said suction-producing means from said motor including a clutch device for connecting and disconnecting said suction means with said motor, an outlet for said suction-producing means open to said hopper, an inlet for said suction-producing means,

a fuel-carrying conduit connected at one end with said inlet, with the opposite end of said conduit being movable to pick up stored fuel for feeding to said hopper, and means for controlling the operation of said motor in response to the actuation of said clutch device to connecting and disconnecting positions therefor.

2. In stoker apparatus including a housing having a fuel compartment, and a motor compartment, an electrical motor in said motor compartment having a driving shaft, means for feeding fuel to said fuel compartment by suction including a suction-producing unit supported on said housing, means for driving said suction unit from said shaft including a first member mounted on said shaft for rotation therewith, and a second member rotatable on said shaft and movable axially of said shaft into and out of driven engagement with said first member, means connecting said suction unit in a driven relation with said second member, actuating means for said second member movable to a first position to axially move said second member into driven engagement with said first member and movable to a second position to release said second member from said driven engagement, an outlet for said suction unit open to said fuel compartment, an inlet for said suction unit having an end portion movable to positions to pick up stored fuel for feeding to said fuel compartment, a control switch in the circuit for said motor, means responsive to the movement of said actuating means to operate said switch, said actuating means being manually movable to said first position to operate said switch to a circuit closing position, and means responsive to a rise of the fuel in said fuel compartment to a substantially filled level to move the actuating means to said second position, with said actuating means, on movement to said second position, operating said switch to a circuit opening position.

3. In stoker apparatus including an electrical motor and a fuel hopper, means for feeding fuel into said fuel hopper by suction including a suction-producing unit supported on said hopper, an outlet for said suction unit open to said fuel hopper, an inlet for said suction unit having a portion movable to positions to pick up stored fuel for feeding to said fuel hopper, means connecting said suction unit for operation by said motor including a clutch device movable to a first operating position to disconnect said suction unit from said motor, and to a second operating position to connect said suction unit with said motor, a control switch in the electrical circuit for said motor, means responsive to the movement of said clutch device to said first operating position to open said control switch, and to the movement of the clutch device to said second operating position to close said switch, and means responsive to a rise of the fuel in said fuel hopper to a substantially filled level to actuate said clutch device to said second operating position.

4. In stoker apparatus including a hopper, means for feeding fuel from a storage bin into said hopper including an upright outlet portion having its lower end open to the space within said hopper, a motor for operating said feeding means, a control switch in the circuit of said motor for controlling the operation of said motor, a fuel contacting member slideably supported for up and down movement on said outlet portion, and actuating means for said control switch including a portion movable into an engaging position with said fuel contacting member, with said fuel

contacting member being movable upwardly by the fuel in said hopper, on a rise of the fuel to a substantially hopper filled level, to engage and move said portion to actuate said switch to a circuit opening position to stop said motor.
